UNITED STATES PATENT OFFICE.

JOHN ADOLPH JOHNSON, OF MERIDEN, CONNECTICUT, ASSIGNOR TO THE M. B. SCHENCK COMPANY, OF MERIDEN, CONNECTICUT, A CORPORATION OF CONNECTICUT.

SOCKET STRUCTURE FOR CASTERS.

1,232,688.

Specification of Letters Patent. Patented July 10, 1917.

Application filed November 27, 1916. Serial No. 133,669.

To all whom it may concern:

Be it known that I, JOHN ADOLPH JOHNSON, a citizen of the United States, residing at the city of Meriden, county of New Haven, State of Connecticut, have invented 5 certain new and useful Improvements in Socket Structures for Casters; and I do declare the following to be a full, clear, and exact description of the invention, such as 10 will enable others skilled in the art to which it appertains to make and use the same.

This invention relates to furniture casters, but more particularly has reference to the 15 socket structure which is secured to a piece of furniture preparatory to receiving the pintle of the caster.

In socket casters it is desirable that the pintle shall rotate but without producing any disagreeable noise, that the end and 20 lateral thrusts of the pintle shall be noiseless and accompanied by a minimum wear, and that there shall be no loosening of parts due to constant use of the caster.

The first two of these ends aimed at have 25 been heretofore accomplished in a great measure by providing anti-friction blocks at the top of the socket to withstand the end thrust of the pintle, and also by providing anti-friction rings around the base of the 30 pintle to take the lateral thrust of the pintle.

But unless the parts are assembled and so united in one rigid structure as to successfully reinforce the resistance of the 35 thrusts and strains of the pintle, the caster as a whole becomes in a short time shaky and wobbly with a decided tendency to produce disagreeable noises as the furniture is shifted or moved about.

40 It is the especial object of the present invention to so assemble and rigidly unite together the several elements of the socket structure that the above noted disadvantages cannot be present, thus not only contributing to the efficiency but to the durability of the caster.

Referring to the accompanying drawings

Figure 1 is a sectional elevation of my improvement, as a whole, applied to a piece 50 of furniture, and

Fig. 2 a series of elevations, partly in section, showing the separate parts, which,

in assembled condition, constitute my improved socket structure.

Similar numerals of reference denote like 55 parts in the several figures of the drawing.

In the first place, it is considered of the greatest importance that the usual track-plate and cup member should be primarily rigidly united together and that said plate 60 should inclose the cup and parts contained therein, so as to exclude all dust and foreign matter. Therefore, the bottom or floor 1 of the track-plate 2 has a central opening 3 that is bounded by a wall 4, so as to provide a hollow inwardly extending open hub 5. A cup member 6 with its bottom or floor level and having a central opening 7 of such size as to snugly embrace the hub 5 is then placed within the part 2 and the upper edge of said hub is forced outwardly and downwardly firmly against the bottom of this member 6, after the manner of eyelet setting. 70

This gives, in effect, two concentric and 75 spaced apart cups that are substantially integral, so that each will contribute to the resisting of any strains that might be brought to bear by virtue of a caster pintle extending therethrough.

8 is a ring of any suitable anti-friction material, such as vulcanized fiber, which is fitted snugly within the member 6, and whose inner circumference extends slightly into the passageway for the pintle, this ring 85 being seated firmly against the bottom of said member, or, more properly speaking, against the turned over edge of the hub 5.

9 is an elongated socket, preferably 90 formed from a sheet metal blank, partially closed in at the top as shown at 10 to afford a shoulder to retain one or more disks 11 of anti-friction material that are inserted at the bottom of the socket and pushed upward to the top thereof. 95

At the bottom of the socket is an outwardly extending flange 12, and within the socket is housed a tubular tapered spring 13 which has a flange 14 at its bottom that underlies the flange 12. The object of the 100 flange 14 is merely to keep the spring in position, but since this is a very immaterial part of the structure and one which may be omitted or modified in various ways, I

lay no stress whatever on it and do not wish to be limited with regard thereto. Moreover, the socket and tubular spring as shown herein are not new and therefore form no 5 part of the present invention.

The socket 9 with the spring 13 is placed within the cup member 6 with the flange 12 supported by the ring 8, and the upper edge of the member 6 is then forced inwardly 10 and downwardly and firmly against said flange so that it will be clear that the track plate 2, member 6, ring 8, and socket 9, are not only all rigidly secured together as an 15 unitary structure, but that the interior of the member 6 and socket 9 are dust proof.

15 is the caster pintle having a lower enlargement 16 as a journal to contact the ring 8, and an upper enlargement 17 to contact the anti-friction element 11, and 18 is a 20 circumferential shoulder intermediate the ends for engagement with the tubular spring 13 when the pintle is inserted in the socket.

The load is carried by the top of the 25 pintle which bears against the material 11, while the lateral strains are exerted against the ring 8.

It will therefore be clear that these lateral strains will be resisted both by the 30 track-plate and by the member 6 and that no strain whatever is placed upon the main body portion of the track-plate. Moreover, whatever strain is placed upon the track-plate is directed to a part of the latter 35 which is reinforced by the clamping of the walls of the hub 5 against the floor of the member 6.

The construction thus afforded is capable of withstanding the roughest usage, and 40 cannot be disrupted or loosened, so far as its practical integrality is concerned, by vertical or lateral strains.

The pintle is secured to the usual horn 19 within which the roller 20 is journaled in 45 the usual manner.

What is claimed is:—

1. A furniture caster socket, comprising a track plate and a cup shaped member primarily rigidly secured together, an anti-friction ring snugly fitting within said member, and a pintle socket having a bottom flange supported within said member upon said ring and secured by bending and clamping the edge of said member against 55 said flange.

2. A furniture caster socket, comprising

a track plate having in its floor a centrally located upstanding open hub, a cup shaped member snugly surrounding said hub the edge of the latter being bent outwardly and 60 forced down against the floor of said member, an anti-friction ring within said member, and a tubular socket with spring element therein and having a bottom flange seated upon said ring and secured by bending and forcing the edge of said member against said flange.

3. A furniture caster socket, comprising a socket having an outwardly extending flange at its bottom, a tubular spring element contained within said socket, a track plate having a centrally disposed and inwardly projecting open hub, a cup shaped member seated on said plate and having an opening which snugly surrounds said hub 75 the end of which latter is bent and clamped against the floor of said member, and an anti-friction ring seated within said member, said socket flange seated on said ring and the upper edge of said member bent 80 and firmly clamped against said flange, whereby all the aforesaid parts will form a unitary structure.

4. In a furniture caster socket, a track plate having projecting upwardly therefrom 85 and centrally located an open hub, and a cup shaped member perforated to snugly embrace said hub and resting upon the floor of said plate and secured thereto by forcing the upper edge of said hub outwardly 90 and downwardly against the floor of said member.

5. A furniture caster socket, comprising a track plate and cup member primarily rigidly secured together and having coinciding 95 central openings for the caster pintle, an anti-friction ring snugly seated in said member and adapted to afford a bearing for the base of said pintle, and a socket member containing a tubular spring member for 100 locking engagement with said pintle, said socket member having a base flange that is contained within said cup member and is seated upon said ring with the upper edge of this cup member forced inwardly and 105 downwardly firmly against said flange.

In testimony whereof I affix my signature in presence of two witnesses.

J. ADOLPH JOHNSON.
